UNITED STATES PATENT OFFICE.

IDA W. SCHMIDT, OF NEW YORK, N. Y.

INVALID-CHAIR AND TRACTOR THEREFOR.

No. 806,296.

Specification of Letters Patent.

Patented Dec. 5, 1905.

Application filed December 7, 1903. Renewed October 26, 1905. Serial No. 284,467.

To all whom it may concern:

Be it known that I, IDA W. SCHMIDT, a citizen of the United States, residing in the city, county, and State of New York, have invented 5 an Improved Invalid-Chair and Tractor Therefor; and I do hereby declare the following to be a full, clear, and exact description of the invention, such as will enable others skilled in the art to which it appertains to make and use 10 the same, reference being had to the accompanying drawings, and to characters of reference marked thereon, which form a part of this specification.

The object of this invention is to combine a 15 wheel-chair and a tractor for driving the same in such manner that the chair may be either used with the tractor or be detached therefrom, so as to be used alone. By providing the chair with a tractor detachable at will the 20 practical range of movement of the vehicle is materially increased. Thus the chair can be either pushed about by an attendant within the more or less limited area of movement of the ordinary invalid-chair or used for touring.

25 In carrying out my invention I preferably employ a chair of the type of that illustrated in my copending application, Serial No. 148,491, and combine it with some suitable tractor in such manner as to render the chair capable of 30 standing the deteriorating effects of road use, while retaining in appearance, lightness, &c., its adaptability for use as an ordinary invalid-chair.

My invention will be found fully illustrated in the accompanying drawings, wherein—

Figure 1 is a view in side elevation thereof, the chair and tractor being assembled so as to use the chair for touring. Fig. 2 is a view, 40 partly in section and partly in side elevation, of the chair as used when pushed about by an attendant; and Figs. 3, 4, 5, and 6 are detail views of certain portions of the chair.

The body of the chair comprises as its essential features a seat *a*, side bars *b*, arms *c*, and back *d*, pivotally associated together and with the seat *a* in such manner as to be adjustable to various positions (see the dotted lines in Fig. 1) by manipulating a set-screw *e*, 45 controlling an adjusting device *f*, pivotally connecting each arm with the back, and foot-rests *g*, pivoted in between the side bars. Depending from the front portion of the seat are two tubular side bars *h*, each carrying at its 50 lower end a tubular *T* *i*, made rigid with the rear portion of the seat by a brace *j*. In the

horizontal portion of each *T*, which is made as a clamp *k*, is adjustably arranged a tubular bar *l*, the two bars *l* being connected by an inverted-U-shaped tubular portion *m*. (See 60 Fig. 3.) At its middle portion the frame thus formed by tubes *l* and *m* carries a bracket *n*, which at *o* forms a vertical hollow bearing for the spindle of a fork *p*, in which is journaled a steering-wheel *q*, the spindle being held in 65 place by a milled nut *r* and carrying a steering-handle *s*. By removing nut *r* the steering device comprised in parts *p*, *q*, and *s* may be removed. By manipulating clamp *k* it may be seen that the frame comprising parts *l* and *m* may be adjusted forward and back.

t designates the main axle, and *u* the main wheels fixed thereon. The springs *v* of the chair are sustained by brackets *w*, (see Fig. 5,) carried by the axle and one of which is bolted 75 to each spring.

x denotes brackets whereby the seat *a* is sustained on the springs, the same being bolted to the springs and having slotted flanges *y*, through which extend threaded studs *z*, projecting from a plate *1* on the under side of the seat *a*, said studs carrying wing-nuts *2* for clamping the plate *1* firmly to the brackets *x*. (See Fig. 6.) The adjustment thus afforded makes it possible to shift the chair bodily 85 backward, so as to bring its center of gravity as much as possible over the axle while the chair is being used with the tractor, it being noticed that at this time it has no other support (the steering-wheel *q* being removed) than 90 the parts *x* afford.

3 is a handle pivoted at 4 to the back *d* of the chair, so that it may be either used by an attendant to push the chair about (at which time it is held horizontally by a wing-nut 5) 95 or folded down, as when the chair is being used with the tractor.

The brackets *w* carry a tubular bar *6*, arranged parallel with the axle *t* and carrying centrally another bracket *7*, formed with a lined 100 bearings *8*. In these bearings is journaled, by means of a suitable bolt *9*, a *T* *10*, in which the forward ends of horizontal side bars *11* of the frame of the tractor are secured. These side bars carry uprights *12* and *13*, the latter 105 of which stand vertical for a portion of their length up from the side bars and are then bent at an incline rearwardly, thus bringing the center of gravity of the seat *14*, which said uprights carry, approximately over the axle *15* of the tractor, said axle being journaled in the uprights *13*.

The motor is indicated at 16, it being an electric motor of any suitable type.

17 is the storage battery from which the source of power for driving the motor is taken, the same being sustained on a support 18, secured to the uprights 12 and 13.

19 represents suitable electrical connections between the battery and the motor, and 20 is a controller of any suitable type.

21 is a band-brake engaging the periphery of a disk 22, fixed on the axle, the band-brake being worked from a foot-lever 23.

24 is the steering-handle, the same being pivoted to the bracket 7 in the upper end thereof. It will be understood that this handle is attached when the tractor is being employed to drive the chair, at which time the steering mechanism comprised in parts *p*, *q*, *r*, and *s* is removed. The vehicle, comprising the chair and the tractor, is thus steered by turning the chair bodily by means of the handle 24 on the bolt 9 as a pivot.

25 25 is a foot-rest supported on the side bars 11 of the tractor by means of rests 26.

Having thus fully described my invention, what I claim as new, and desire to secure by Letters Patent, is—

1. In a vehicle, the combination of a wheel-chair, a motor or tractor having a pivotal con-

nexion therewith and arranged back of the same, and a means projecting from the chair toward the tractor and fixed to the chair against movement therein laterally thereof, for turning the chair relatively to the tractor whereby to steer the vehicle substantially as described.

2. The combination, in a wheel-chair, of the axle and wheels, the chair proper, and means for supporting the chair on the axle, said means being adapted to permit of a forward and back adjustment of the chair proper thereon, substantially as described.

3. In a wheel-chair, the combination of the chair proper, the axle and wheels, means for supporting the chair on the axle, and a tubular structure arranged in the front lower portion of the chair and adapted to carry a steering-wheel, said structure being adjustable forward and back in the chair, substantially as described.

In testimony that I claim the foregoing I have hereunto set my hand this 30th day of October, 1903.

IDA W. SCHMIDT.
